(57) **CLAIM**

The ornamental design for a manual roller vegetable chopper, as shown and described.

DESCRIPTION

FIG. 1 is a front elevational view of a manual roller vegetable chopper showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is another perspective view thereof;

FIG. 9 is a front elevational view of a second embodiment of a manual roller vegetable chopper showing my new design;

FIG. 10 is a rear elevational view thereof;

FIG. 11 is a left side view thereof;

FIG. 12 is a right side view thereof;

FIG. 13 is a top plan view thereof;

FIG. 14 is a bottom plan view thereof;

FIG. 15 is a perspective view thereof;

FIG. 16 is another perspective view thereof;

FIG. 17 is a front elevational view of a third embodiment of a manual roller vegetable chopper showing my new design;

FIG. 18 is a rear elevational view thereof;

FIG. 19 is a left side view thereof;

FIG. 20 is a right side view thereof;

FIG. 21 is a top plan view thereof;

FIG. 22 is a bottom plan view thereof;

FIG. 23 is a perspective view thereof;

FIG. 24 is another perspective view thereof;

FIG. 25 is a front elevational view of a fourth embodiment of a manual roller vegetable chopper showing my new design;

FIG. 26 is a rear elevational view thereof;

FIG. 27 is a left side view thereof;

FIG. 28 is a right side view thereof;

FIG. 29 is a top plan view thereof;

FIG. 30 is a bottom plan view thereof;

FIG. 31 is a perspective view thereof; and,

FIG. 32 is another perspective view thereof.

The broken lines depict portions of the manual roller vegetable chopper that form no part of the claimed design.

1 Claim, 32 Drawing Sheets
